The medical probe is longitudinal, with a head on its one end and a connector with a flexible cable on the other; the narrow part of the probe located next to the head is equipped with eight measuring electrodes; six electrodes are longitudinal and evenly distributed around the probe circumference along its axis; two others—in form of rings—are placed perpendicularly to them, at their ends; in the next part of the probe its diameter widens gradually creating a handle with markers in form of rows of grooves distributed around its circumference.
